WEDGE BOLT

Richard Valentine Johnson, Clifton Forge, Va.

Application September 2, 1938, Serial No. 228,245

2 Claims. (Cl. 105—81)

This invention relates to a wedge bolt designed primarily for use in connection with the driving box of a locomotive, one of the objects being to provide an interchangeable wedge bolt which can be placed in position or removed from position without the necessity of dismantling the structure in which the driving box is located and without removing the wedge.

A further object is to provide an interchangeable wedge bolt which, after being placed in position, will be held securely against accidental displacement.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawing the preferred form of the invention has been shown.

In said drawing:

Figure 1 is a view partly in elevation and partly in section showing the interchangeable wedge bolt in position.

Figure 2 is a section on the line 2—2, Figure 1.

Figure 3 is a section on line 3—3, Figure 1.

Figure 4 is a section on line 4—4, Figure 1.

Figure 5 is a section on line 5—5, Figure 1.

Referring to the figures by characters of reference 1 designates a portion of the underframe of a locomotive, the same being provided with the usual pedestals 2 connected at their lower ends by a pedestal brace or binder 3. These are of standard construction, the brace being held to the pedestals by the usual bolts 4.

The wedge has been indicated at 5 and differs from other wedges in that it is provided at its lower or large end with a substantially circular opening 6 extending entirely through it and located at the upper end of a slot 7 which extends through the bottom of the wedge.

The wedge bolt has been indicated at 8 and is formed with a longitudinal keyway which can be in the form of a groove 9. This bolt has a substantially circular head 10 provided with opposed flat faces, the diameter of the head being such that it can be seated within the opening 6 while the threaded stem portion of the bolt is seated in the slot 7. Opposed faces of the head 10 are rounded at opposite sides respectively, as shown at 11 so that if the head has been inserted edgewise into the opening 6, it can subsequently

be rotated to bring it into position transversely of the opening and as shown in Figures 1, 2 and 4.

The pedestal brace 3 is formed with a slot 12 extending therethrough under the slotted end of the wedge 5 and bolt 8 extends through this slot along one end wall thereof. The remaining portion of the slot is filled with a wedge 13 fitting snugly therein and extending from top to bottom of the brace 3, this wedge being shaped at one side so as to snugly embrace the adjacent portion of bolt 8. The wedge is also provided with an integral key 14 adapted to project into groove 9.

A retaining plate 15 is pivotally mounted on one of the bolts 4 and has an arcuate slot 16 extending thereinto from one side. This slot is so located that when the retaining plate is swung into position beneath and parallel with the brace 3, the bolt 9 will be received within the slot. When the plate is thus located, as shown for example in Figure 3, the wedge 13 will be supported thereby so that it cannot drop out of its slot 12. Plate 15 can be held in retaining position in any suitable manner. For example it may be formed with an offset 17 providing a recess for the reception of a node projecting from brace 3.

A yoke 18 is located under brace 3 and is held in position at its ends by the bolts 4. The middle portion of this yoke is spaced from brace 3 and has an opening 19 adapted to receive bolt 8. Nuts 20 engage the bolt and are positioned to clamp upon opposed faces of yoke 18 so as thus to lock the bolt against longitudinal movement after it has once been adjusted.

When it is desired to assemble the wedge bolt with the wedge 5, it is not necessary to take apart the adjacent locomotive structure. It is merely necessary to remove the yoke 18 and swing the retaining plate 15 laterally from under slot 12. The key 13 in the slot is then removed downwardly after which the bolt 8, with the upper nut 20 in position thereon, is inserted head first upwardly through the slot 12 and slot 7 until the head 10 arrives within the opening 6. The nut is then given a one-quarter turn so as to bring the head into position transversely of opening 6. Thereafter key 13 is inserted into slot 12 so that the rib or pin 14 will be within the groove or channel 9. This will hold the bolt 8 against rotation relative to the wedge 5. Supporting plate 15 is then swung into position under the key 13 after which the yoke 18 is placed on the lower end of bolt 8 and secured in place at its ends by the bolts 4. By now turning the up-

- per nut 20 the bolt 8 can be adjusted upwardly, causing the wedge 5 to move upwardly therewith and after the desired adjustment of the wedge has been effected, the other nut 20 is placed on 5 the bolt and tightened against the yoke, thereby constituting an effective lock for holding the bolt against further longitudinal movement. To remove the bolt the foregoing operation is merely reversed.
- 10 By providing a structure such as herein described, a wedge bolt can be readily replaced with a new one should it become broken, this removal being effected without the necessity of removing the pedestal brace or binder 3.
- 15 What is claimed is:
1. The combination with a structure for holding a driving box, said structure including a slotted brace, of a wedge in said structure overlying the slot in the brace, said wedge having a slot extending thereinto from its lower end, the upper end of the slot opening into a substantially circular opening extending through the wedge and of greater diameter than the width of the slots in the wedge and brace, a wedge bolt having 20 a longitudinal keyway and a flat substantially circular head, said bolt and head being insertable upwardly through the slots in the brace and wedge and rotatable through approximately ninety degrees to position the head transversely of and within the opening in the wedge, a key slidable along the keyway of the inserted bolt and within the brace slot for holding the bolt against rotation, means for removably support-
  - 25
  - 25
  - 30

ing the key in said slot independently of the bolt, and means for adjusting the bolt longitudinally to correspondingly adjust the wedge, said means including a yoke detachably connected to the brace and through which the bolt extends, and a nut engaging the bolt and yoke for transmitting thrust therebetween.

2. The combination with a structure for holding a driving box, said structure including a slotted brace, of a yoke secured to and located 10 under the brace, a wedge in said structure overlying the slot in the brace, said wedge having a slot extending thereinto from its lower end, the upper end of the slot opening into a substantially circular opening extending through the wedge 15 and of greater diameter than the width of the slots in the wedge and brace, a wedge bolt having a longitudinal keyway and a flat substantially circular head, said bolt and head being insertable upwardly through the slots in the brace and wedge and rotatable through approximately ninety degrees to position the head transversely of and within the opening in the wedge, a key slidable along the keyway of the inserted bolt and within the brace slot for holding the 25 bolt against rotation, means for removably supporting the key in said slot independently of the bolt, said means including a retaining plate pivotally mounted between the brace and yoke and having an arcuate bolt-receiving slot extending 30 thereinto from one edge.
